UNITED STATES PATENT OFFICE.

DAVIS MARINSKY, OF NEW YORK, N. Y.

SEALING-MACHINE.

1,309,147.

Specification of Letters Patent. Patented July 8, 1919.

Application filed April 19, 1918. Serial No. 229,523.

To all whom it may concern:

Be it known that I, DAVIS MARINSKY, a citizen of the United States, and residing at New York, in the county of Bronx and State of New York, have invented certain new and useful Improvements in Sealing-Machines, of which the following is a specification, such as will enable those skilled in the art to which it appertains to make and use the same.

This invention relates to sealing machines and particularly machines of this class designed for sealing folders, circulars, pamphlets and the like, and the object of the invention is to provide an improved machine of this class which is automatic in operation, simple and compact in construction and which is so constructed as to not easily get out of order, or need repair, and a further object of the invention is to provide a machine of the character set forth which is designed to seal articles of various kinds and classes and of different thicknesses without any change in the construction of the machine, or the various parts employed; and with these and other objects in view the invention consists in a machine of the class specified, constructed and operating as hereinafter described and claimed.

The invention is fully disclosed in the following specification, of which the accompanying drawings form a part, in which the separate parts of my improvement are designated by suitable reference characters in each of the views, and in which:

Figure 1 is a side view of my improved machine with part of the construction shown in section;

Fig. 2 a longitudinal section of my improved machine, the section being on the line 2—2 of Fig. 3;

Fig. 3 a sectional plan view of the machine, the section being on the line 3—3 of Fig. 2;

Fig. 4 a partial section on the line 4—4 of Fig. 2;

Fig. 5 a section on the line 5—5 of Fig. 2;

Fig. 6 a partial section on the line 6—6 of Fig. 3, and on an enlarged scale and with part of the construction broken away;

Fig. 7 a partial section on the line 7—7 of Fig. 2;

Fig. 8 a partial section on the line 8—8 of Fig. 3;

Fig. 9 a view similar to Fig. 8 with parts shown in a different position;

Fig. 10 a diagrammatic view of the mechanism employed for automatically putting certain mechanisms of my improved machine into operation;

Fig. 11 a diagrammatic view showing the sealing strip, feeding, cutting, moistening and compressing means and indicating the operation thereof; and,

Fig. 12 a sectional and perspective view of a sealed article and showing the sealing member applied thereto.

In the drawings, 20 is a main or base frame which is approximately oblong in form and the opposite sides of which are provided with enlarged portions 21 and the central portion of said base 20 is provided with upwardly directed flanges 22 as clearly shown in Fig. 5.

Secured to the upwardly directed flanges 22 are inner vertical frame members 23, and secured to the outer enlarged portions 21 at the sides of the frame, are outer vertical frame members 24. The inner and outer frame members are connected at the top by a sheet metal facing 25 as clearly shown in Figs. 1, 2, 3 and 5, said facing extending the full length of the outer vertical frame members 24.

The outer vertical frame members 24 are provided approximately centrally thereof with upwardly directed arms 26, the tops of which form bearings for a transverse drive shaft 27 on which is mounted a vertically movable frame 28, comprising an approximately rectangular housing portion 29 provided with a central and backwardly directed arm 30 which joins two laterally directed arms 31 in a hollow box-shaped cross head 32.

Connected with the drive shaft 27 at one end thereof is a pulley 33 driven by a belt 34 passed therearound, said belt being operated from a pulley on a motor or power shaft not shown, and secured to the opposite end of the shaft 27 is a gear 35 which meshes with a gear 36 secured to a shaft 37 mounted in the outer frame members 24, and a gear 38 is secured to a shaft 39 mounted in the outer frames 24 and the inner frames 23, the gear 38 being in mesh with the gear 36, as clearly shown in Fig. 1.

Secured to the shaft 39 within the frame

members 23 is a crank 40, known as a "geneva" crank, adapted to operate in connection with a rotary member or "geneva" 41 which is clearly shown in Fig. 2, the end 5 of the crank 40 being provided with a flanged roller 42 adapted to operate in connection with the grooves 43 in the geneva as will be readily understood. The geneva 41 is mounted to move longitudinally of a shaft 10 44 secured in one of the frame members 23 and passing through the other. The geneva 41 is provided with a sleeve portion 45 which passes through an aperture 46 in one of the frame members 23 and inwardly 15 of said frame member, the sleeve portion 45 of the geneva is provided with a gear member 47. The geneva 41 is operated in one direction by a cam member 48 secured to the shaft 39 between the frame members 20 23 and in the opposite direction by springs 49 secured to a cross head 50 mounted on the protruding end of the shaft 44, and a ball bearing 51 is placed between the cross head 50 and a shoulder on the end portion of said 25 shaft, as clearly indicated in Figs. 3 and 8 of the drawing.

The inner vertical frame members 23 are provided with forwardly directed extensions 52 in which is mounted a transverse shaft 30 53, on which a roll of gummed paper 54 is rotatably mounted, and rotatably mounted in the inner frame members 23 are feed rollers 55 between which the gummed strip of paper 54 is adapted to pass, as clearly 35 shown in Fig. 2, and mounted in said frame members above the feed rollers 55 are rotary cutting devices 56 and 57. The device 56 constitutes a roller of hardened steel while the device 57 consists of a tool steel roller, 40 the periphery of which is provided on opposite sides thereof with knife edges 58 which operate in connection with the roller 56 to cut the gummed strip as it passes therebetween.

45 Feeding and moistening rollers 59 are mounted in the frame members 23 above the rotary cutting devices 56 and 57 and in operative connection with one of said rollers is a moisture applying roller 60, which is mounted 50 in the frame members 23 and in the inner end portion of a pan member 61 which forms a container for water or other suitable liquid, the pan member 61 being detachably connected with the frame members 23 55 by a groove construction as shown at 62 in Fig. 7, and held in its operative position by headed screws 63 and winged nuts 64.

The roller 56 of the rotary cutting devices is mounted in the inner end portion of 60 blocks 65, mounted to move longitudinally of elongated apertures 66 in the frame members 23 against the tension of springs 67 mounted on rods 68 which pass through said blocks and through the front end portions of 65 the frame members 23, and the tension of

the springs 67 may be adjusted by manipulating nuts 69 on the ends of the rods 68.

One of the feed rollers 55 is mounted in blocks 65 in the same manner as the mounting of the roller 56 of the rotary cutting devices as clearly shown in Fig. 6 of the drawing, and with this construction the tension of the rollers 56 and 55 may be regulated at all times.

75 Mounted in the top portion of the frame members 23 are blocks or strips 70 which are adjustable longitudinally thereof by means of screws 71 adjustably mounted in the front end of said frame members, as clearly shown in Fig. 3, and one of the feeding and 80 moistening rollers 59 is mounted in the inner end portion of said block 70, as clearly shown in Figs. 2 and 3, and mounted centrally of said block is a workpiece feed roller 72, and mounted in the inner end portion of the frame members 23 is another workpiece feed roller 73.

85 Secured to the shaft 39 adjacent to one of the frame members 23 is a gear 74 which meshes with a gear 75 mounted between said frame member 23, and a supplemental frame member 76, the form of which is indicated in full and dotted lines in Fig. 6 of the drawing and is shown in section in Fig. 3. The gear 75 meshes with another gear 77 95 mounted on an extension of the feed roller 73, and one of the feed and moistening rollers 59 is provided with a gear 78 which is placed in operative connection with the gear 77 by a chain of gears 79, three of which are 100 shown, and the other of said feed and moistening rollers 59 is provided with a gear 80 placed in operative connection with the gear 78 by gears 81 and 82, and it will be noted that all the gears 75, 77, 78, 79, 81 and 82 105 are mounted between one of the frame members 23 and the supplemental frame member 76. The gears 79, are provided with laterally directed studs as clearly indicated in Fig. 3 of the drawing as are also the gears 81 and 82, and these studs serve as bearings for supporting said gears, while the gears 78 and 80 are mounted in the ends of the rollers 59, as clearly indicated in said figure.

110 The workpiece feed roller 72 is provided with a gear 83 placed in communication with the gear 80 by two smaller gears 84 which are mounted on the ends of rods 85 secured in the frame members 23, as clearly 115 shown in Fig. 3. With this construction it will be seen that all of the rollers 59, 72 and 73 are constantly in operation, or are driven from the drive shaft 27 through the gears 35, 36 and 74. It will be noted that 120 the top sheet metal covering 25 of the frame members 23 and 24 is cut out where the rollers 72, 59 and 73 pass therethrough and as clearly shown in Fig. 3, it will be noted that the blocks 70 are connected approxi- 130

- mately centrally thereof by a rod 86 which holds said blocks in the frame members 23 against displacement, the outer and bottom faces of said blocks being flanged as shown 5 at 87 and adapted to fit in corresponding recesses in the frame members 23 to prevent their inward movement, as will be readily understood, and as clearly indicated in Fig. 7 of the drawing.
- 10 Secured to the ends of the feed rollers 72 and 73 outwardly of the frame members 23 are supplemental workpiece feed rollers 88 and 89. The front end portion of the inner frame members 23 are connected by 15 rods 90 and 91, the rod 91 extending through one of the frame members 23 and mounted on said extension is a rearwardly directed arm 92. The pivot end of said arm is provided with an upwardly directed lug 93 20 with which is connected a spring 94 which is also connected with the adjacent end of the rod 90 as indicated at 95 in Fig. 2, and this construction is shown clearly in Figs. 2 and 10 of the drawing. Secured to the 25 rod 91 approximately, centrally thereof is a hook-shaped finger device 96, the hook-shaped end 97 of which is adapted to operate in connection with the material or workpiece 98 fed into the machine and to be 30 moved by said workpiece into a groove 99 centrally of the feed roller 72, as clearly indicated in Fig. 10.
- Secured to one of the frame members 23 adjacent to which the arm 92 is mounted 35 and near the rear end portion of said main frame member is a stop and guide nut 100 comprising an elongated rectangular head 101 offset from the side of the frame member 23 by a neck portion 102, and the rear 40 end of the arm 92 is adapted to operate between the elongated rectangular head 101 of the device 100 and the adjacent frame member 23 and the outer face of the sleeve portion 45 of the geneva 41, as clearly indicated 45 in Figs. 8, 9 and 10 of the drawing, this mechanism involving the arm 92 and finger 96, which forms an automatic starting mechanism for my improved machine.
- Each of the feed rollers 55 is provided adjacent to one of the frame members 23 with 50 gears 103, one of which is shown in Fig. 5 of the drawing and which are in operative connection and are also in mesh with the gear 47 on the sleeve 45 of the geneva, while 55 the rotary cutting devices 56 and 57 are also provided with the gears 104 similar to the gears 103 in all respects, and which are also in operative connection with the gear 47 on the sleeve of the geneva 41, and by this construction when the geneva is rotated by the 60 geneva crank 40, the feed rollers 55 and rotary cutting devices 56 and 57 are rotated to feed the gummed strip 54 and to cut off a predetermined length of said strip as herein- 65 after described.
- One of the feed rollers 55 is provided with a shaft extension 105 carrying a worm 106 which operates in connection with a worm gear 107 secured on one end of a shaft 108, mounted in bearings 109 secured to the corresponding frame member 23 as clearly shown in Fig. 6, and secured to the opposite end of said shaft is a helical or spiral gear 110 which meshes with a corresponding gear 111 secured to a shaft 112 mounted in the frame members 24, as clearly shown in Fig. 3 of the drawing. Secured to the shaft 112 at spaced intervals are a plurality of pulleys 113 around which are passed belts 114 which also pass around corresponding pulleys 115 spaced on and rotatably mounted on a rod 116 adjustably mounted in backwardly directed extensions 117 of the outer frame members 24, as clearly indicated in Figs. 1 and 3 of the drawing. It will be noted that the sheet metal facing 25 is cut out as shown at 118 to permit the pulleys 113 to pass therethrough and the belt 114 to pass over the top of said sheet backwardly to the pulleys 115, and with this construction the sealed workpieces 98, one of which is shown in Fig. 12 of the drawing, may be collected and fed from said machine as will be readily understood, and a number of these are indicated at 119 in Fig. 1 of the drawing.
- The front and rear end portions of the outer frame members 24 are connected and reinforced by heavy rods 120, and these rods in combination with the connection of the frame members 24 with the base 20 serve to 100 space said frame members as will be readily understood.
- Mounted on the shaft 27 within the box-shaped cross head 32 is a beveled gear 121 which meshes with a corresponding gear 105 122, secured to one end of a shaft 123 mounted in the arm 30 as clearly indicated in Figs. 2 and 4 of the drawing, and secured to the other end of said shaft is a beveled gear 124 which meshes with a corresponding beveled gear 125 secured to a transverse shaft 126 mounted in the vertically movable frame 28 or the housing 29 thereof. Secured to the shaft 126 adjacent to one end thereof and within the housing 29 is a gear 127, which meshes with a gear 128 rotatably mounted on a shaft 129 mounted in the housing 29 forwardly of and beneath the shaft 126, and secured to the opposite end portions of the shaft 129 are brackets 130 having upwardly directed arms 131 and forwardly directed arms 132.
- The free ends of the arms 131 are connected by a transverse rod 133 on which is rotatably mounted adjacent to one of the arms 131 a flanged anti-friction roller 134 which operates in connection with a cam 135 secured to the shaft 126, as clearly indicated in Figs. 2 and 4 of the drawing. The free ends of the other arms 132 are connected by 130

a shaft 136 carrying a plurality of enlarged feed rollers 137 which operate in connection with the workpiece feed rollers 72 and 88, and springs 138 are connected at 139 with the free ends of the arms 132 and with the housing portion 29 of the vertically movable frame 28, as shown at 140 in Fig. 2 of the drawing and serve to hold said arms in the position shown in said figure. A gear 141 is mounted on the shaft 136 in line with the gears 127 and 128 and is in operative connection with the gear 128, and with this gear construction it will be seen that the feed rollers 137 are operated from the shaft 27 through the beveled gears 122, 124 and 125.

The gear 128 is adapted to mesh with a gear construction 142 on a feed roller 143 rotatably mounted in the bottom central portion of the housing 29, as clearly shown in Figs. 2 and 5 of the drawing. A shaft 144 is mounted in the housing 29 rearwardly of and beneath the shaft 126 and a gear 145 is mounted on said shaft, said gear being in operative connection with the gear 127 on the shaft 126 and also in operative connection with a gear 146 mounted on a shaft 147 secured in the rear end portion of the housing 29 and on which is mounted a plurality of large feed rollers 148, which correspond with the feed rollers 137, and which operate in connection with the workpiece feed rollers 73 and 89.

A forwardly directed top finger 149 is secured to a shaft 144^a, and passes through an aperture in a sheet metal facing 150 for the housing 29 as clearly shown in Fig. 2 and against the face of which the articles fed into the machine abut, and which prevents the further feeding of such articles into the machine until an arm 151 secured to the shaft 129 raises said finger out of operative position by the engagement with said finger at 152 as will be readily understood, and it will also be noted that the feed roller 143 also passes through an aperture in the sheet metal facing 150 of the housing 29.

The operation of my improved machine will be readily understood from the foregoing description when taken in connection with the accompanying drawing and the following statement thereof. The position of the various parts of my improved machine as indicated in Fig. 1 might be regarded as their normal positions, or in other words if the drive shaft 27 is operated from any suitable source through the belt 34 and the pulley 33, the shaft 39 carrying the geneva crank 40, cam 48 and gear 74 will be rotated through the gears 36 and 38, the gear 74 rotating the feed rollers 73, 59 and 72 through the gears 75, 77, 79, 78, 81 and 82, 80, 84 and 83, while the feed rollers 137, 148, and 143 are driven by the shaft 27 through the beveled gears 121, 124 and 125 and through the gears 127, 128, 142, 141, 145 and 146. In

other words, when the machine is in operation the feed rollers 72 and 137, 59 and 143, 73 and 148 are constantly rotated by the gear construction as above set out, and in this operation the feed rollers 137 in the 70 housing 29 are moved vertically in one direction by the cam member 135 on the shaft 126 which operates in connection with the flanged anti-friction roller 134 on the brackets 130, and in the other direction by the 75 springs 138, in which operation the stop finger 149 is correspondingly raised and lowered by the operating arm 151 and by gravity, and the operation of these parts will be readily understood on a consideration of 80 Figs. 2 and 10 of the drawing. It will also be noted that in the above described operation of the machine the feed rollers 55 and the rotary cutting devices 56 and 57 are not in operation by reason of the fact that the 85 geneva crank 40 is out of operative connection with the geneva 41, as will be evident on a consideration of Fig. 8 of the drawing.

When the machine is in operation, as above described, if the article 98 to be sealed is fed into the machine, as indicated in Figs. 10 and 11 of the drawing, the same will first strike the stop finger 149, if the parts are in the position indicated in Fig. 2, and when the feed rollers 137 reach the position indicated in Fig. 10 of the drawing, said article is fed farther into the machine and the hook-shaped finger 96 is depressed into the position shown in Fig. 10, and this operation moves the arm 92 into the position shown in 90 said figure, it being understood that the cam 48 is so constructed and timed as to move the geneva 41 on the shaft 44 against the tension of the springs 49, or into the position shown in Fig. 9 of the drawing at the 95 time or slightly in advance of the time at which the arm 92 is moved into the position shown in Figs. 9 and 10, and in this position of said arm the geneva is held thereby against outward movement on the shaft 44 100 by the springs 49, as will be readily understood, and the geneva crank 40 will engage said geneva and rotate it one-quarter of a 105 revolution.

The operation of the geneva 41 rotates the 115 feed rollers 55 and rotary cutting devices 56 and 57 to feed the sealing strip 54 vertically and to cut-off the protruded portion thereof, and this part 153 is picked up by the feed and moistening rollers 59 and is fed into the 120 position as shown in Fig. 11, in which position the edge portion of the workpiece or article 98 to be sealed as it is fed into the machine engages the central portion of said part 153 and forces it between the feed rollers 59 and 143, where it is compressed onto the opposite sides of the article 98 to be sealed, and said article is then fed through the feed rollers 73 and 148 and discharged onto the conveyer belts 114, which carry the 125 130

same rearwardly of the machine where they may be collected and removed therefrom in any desired manner, or said sealed article may be dropped into a suitable box or container.

It will be noted on a consideration of Figs. 3 and 6 of the drawing that the operation of the feed rollers 55 through the geneva 41 also operates the belts 114 by reason of the worm gear construction 106 and 107 and helical or spiral gear construction 110 and 111 which drives the shaft 112 carrying the spools 113.

With the vertically movable frame 28 carrying the feed rollers 137, 143 and 148 workpieces of varying thicknesses may be fed into the machine without changing the construction of said machine, whatever, or without making any adjustment of the various parts of said machine, and the limit of the transverse width of said workpieces will be that of the distance between the outer frame members 24 as will be readily understood, and by providing an automatic machine of the class referred to, it will be impossible to feed a workpiece into the machine farther than the stop finger 148 until the feed rollers 55 and rotary cutting devices 56 and 57 are put in operation through the hook-shaped finger 96 and arm 92 as above set out.

The cam 48 is constantly rotated when the machine is in operation by the shaft 39 through the gears 35, 36 and 38 as is also the geneva crank 40 and at each revolution thereof the geneva 41 is moved longitudinally of the shaft 44, but this movement is such that the crank 40 just misses said geneva, but when the geneva is held by the arm 92 against movement on the shaft 44 by the springs 49 as above set out, the next revolution of the crank 40 will engage the geneva and operate the same as will be readily understood, and it will be noted that the cam face 154 of the cam 48 operates upon a shoulder 155 on the sleeve portion 45 of the geneva.

While I have shown and described the various details of construction for carrying my invention into effect such as an automatic starting mechanism, the means for operating the feed roller and the means for feeding, cutting and moistening the sealing strip employed, it will be understood that changes in and modifications of these details of construction may be made, within the scope of the appended claims, without departing from the spirit of my invention or sacrificing its advantages.

Having fully described my invention, what I claim as new and desire to secure by Letters Patent, is:—

1. In a machine of the class described, a main frame, workpiece feed rollers mounted in said frame, a movable frame mounted

above the main frame, and workpiece feed rollers mounted in said frame and in position to coöperate with the workpiece feed rollers in the stationary frame, means for operating the feed rollers in the stationary frame, means for operating the feed rollers in the movable frame, and means for giving one of said feed rollers in the movable frame an intermittent movement toward and from the corresponding feed roller in the stationary frame.

2. In a machine of the class described, a main frame, feed rollers mounted in said frame, a supplemental frame movable toward and from the main frame, feed rollers mounted in said supplemental frame and co-operating with the feed rollers of the main frame to feed articles to be sealed into and through the machine, means for operating the feed rollers in the main frame, means for operating the feed rollers in the supplemental frame, and means for operating one of said feed rollers in the supplemental frame toward and from the corresponding roller in the main frame.

3. In a machine of the class described, a main frame, feed rollers mounted in said frame, a supplemental frame movable toward and from the main frame, feed rollers mounted in said supplemental frame and co-operating with the feed rollers of the main frame to feed articles to be sealed into and through the machine, means for operating the feed rollers in the main frame, means for operating the feed rollers in the supplemental frame, means for operating one of said feed rollers in the supplemental frame toward and from the corresponding roller in the main frame, means for stopping the feeding of an article to be sealed into the machine, and means for moving said last named means into inoperative position in the operation of said third named means.

4. In a machine of the class described, a main frame, feed rollers mounted in said frame, means for operating said feed rollers, a supplemental frame mounted to move toward and from the main frame, feed rollers mounted in said supplemental frame and adapted to coöperate with the feed rollers of the main frame, means for operating said last named feed rollers, a sealing strip feeding and cutting mechanism mounted in the main frame, and means operated by the article to be sealed as it is fed into the machine for putting said sealing strip feeding and cutting mechanism into operation.

5. In a machine of the class described, a main frame, feed rollers mounted in said frame, means for operating said feed rollers, a supplemental frame mounted to move toward and from the main frame, feed rollers mounted in said supplemental frame and adapted to coöperate with the feed rollers of the main frame, means for operating said

- last named feed rollers, a sealing strip feeding and cutting mechanism mounted in the main frame, means operated by the article to be sealed as it is fed into the machine for putting said sealing strip feeding and cutting mechanism into operation, to cut off a predetermined part of said sealing strip and feed it into position to be compressed onto the article to be sealed, and means for folding and compressing said part onto the article fed into the machine.
6. In a machine of the class described, a main frame, feed rollers mounted in said frame, means for operating said feed rollers, a supplemental frame mounted to move toward and from the main frame, feed rollers mounted in said supplemental frame and adapted to coöperate with the feed rollers of the main frame, means for operating said last named feed rollers, a sealing strip feeding and cutting mechanism mounted in the main frame, means operated by the article to be sealed as it is fed into the machine for putting said sealing strip feeding and cutting mechanism into operation, to cut off a predetermined part of said sealing strip and feed it into position to be compressed onto the article to be sealed, means for folding and compressing said part onto the article fed into the machine, and means for moistening the cut off portion of said sealing strip prior to its folding and compression upon the article to be sealed.
7. In a machine of the class described, a main frame, feed rollers mounted in said frame, means for operating said feed rollers, a supplemental frame mounted to move toward and from the main frame, feed rollers mounted in said supplemental frame and adapted to coöperate with the feed rollers of the main frame, means for operating said last named feed rollers, a sealing strip feeding and cutting mechanism mounted in the main frame, means operated by the article to be sealed as it is fed into the machine for putting said sealing strip feeding and cutting mechanism into operation, to cut off a predetermined part of said sealing strip and feed it into position to be compressed onto the article to be sealed, means for folding and compressing said part onto the article fed into the machine, means for moistening the cut off portion of said sealing strip prior to its folding and compression upon the article to be sealed, conveyer belts mounted in the rear end portion of the main frame, and means for feeding the sealed articles onto said belts.
8. In a machine of the class described, a main frame, feed rollers mounted in said frame, means for operating said feed rollers, a supplemental frame pivoted to the main frame and movable toward and from the same, feed rollers mounted in said supplemental frame, means for operating said

feed rollers, a stop device mounted in the supplemental frame and adapted to control the feeding of articles to be sealed into the machine; a sealing strip feeding and cutting mechanism mounted in the main frame and normally in an inoperative position, and means in the main frame operated by the article to be sealed as it is fed into the machine for putting the said sealing strip feeding and cutting mechanism into operation.

9. In a machine of the class described, a main frame comprising a base member and inner and outer vertical frame members, the outer frame members being provided approximately centrally thereof with upwardly directed arms in which is mounted a drive shaft, a supplemental frame movably mounted on said shaft and capable of movement toward and from the main frame, feed rollers mounted in the top of the main frame, corresponding feed rollers mounted in the bottom portion of the supplemental frame and coöperating with the rollers in the main frame, means for gearing the feed rollers in the main frame in connection with the drive shaft, means for gearing the feed rollers in the supplemental frame in connection with said drive shaft, and means for moving one of the feed rollers of the supplemental frame toward and from the corresponding roller in the main frame.

10. In a machine of the class described, a main frame comprising a base member and inner and outer vertical frame members, the outer frame members being provided approximately centrally thereof with upwardly directed arms in which is mounted a drive shaft, a supplemental frame movably mounted on said shaft and capable of movement toward and from the main frame, feed rollers mounted in the top of the main frame, corresponding feed rollers mounted in the bottom portion of the supplemental frame and coöperating with the rollers in the main frame, means for gearing the feed rollers in the main frame in connection with the drive shaft, means for gearing the feed rollers in the supplemental frame in connection with said drive shaft, means for moving one of the feed rollers of the supplemental frame toward and from the corresponding roller in the main frame, sealing strip feeding and cutting devices mounted in the main frame, and means for operating said sealing strip feeding and cutting devices.

11. In a machine of the class described, a main frame comprising a base member and inner and outer vertical frame members, the outer frame members being provided approximately centrally thereof with upwardly directed arms in which is mounted a drive shaft, a supplemental frame movably mounted on said shaft and capable of movement toward and from the main frame,

feed rollers mounted in the top of the main frame, corresponding feed rollers mounted in the bottom portion of the supplemental frame and coöperating with the rollers in the main frame, means for gearing the feed rollers in the main frame in connection with the drive shaft, means for gearing the feed rollers in the supplemental frame in connection with said drive shaft, means for 5 moving one of the feed rollers of the supplemental frame toward and from the corresponding roller in the main frame, sealing strip feeding and cutting devices mounted in the main frame, means for operating said sealing strip feeding and cutting devices to 10 cut off a predetermined part of said strip and means for feeding said part of the strip into position to be engaged by an article to be sealed as it is fed into the machine and for moistening said part. 15

12. In a machine of the class described, a main frame, a drive shaft mounted therein, feed rollers mounted in the main frame, means for gearing said feed rollers in connection with said drive shaft, a supplemental frame pivoted to said shaft and movable toward and from the main frame, feed rollers mounted in the supplemental frame, means for gearing said feed rollers in connection with said drive shaft, a conveyer 25 mechanism mounted in the main frame, means for gearing said conveyer in connection with said last named means, a sealing strip feeding and cutting mechanism mounted in the main frame and normally in an inoperative position, and means operated by the article to be sealed as it is fed into the machine for putting said sealing strip feeding and cutting mechanism into operation. 30

13. In a machine of the class described, a main frame, a drive shaft mounted therein, feed rollers mounted in the main frame, means for gearing said feed rollers in connection with said drive shaft, a supplemental frame pivoted to said shaft and movable toward and from the main frame, feed rollers mounted in the supplemental frame, means for gearing said feed rollers in connection with said drive shaft, a conveyer 45 mechanism mounted in the main frame, means for gearing said conveyer in connection with said last named means, a sealing strip feeding and cutting mechanism mounted in the main frame and normally in an inoperative position, means operated by the article to be sealed as it is fed into the machine for putting said sealing strip feeding and cutting mechanism into operation to cut off a predetermined part of said strip, and 50 means for feeding said strip into position to be engaged by the article fed into the machine and for moistening said part. 55

14. In a machine of the class described, a main frame, a drive shaft mounted therein, feed rollers mounted in the main frame, 60

means for gearing said feed rollers in connection with said drive shaft, a supplemental frame pivoted to said shaft and movable toward and from the main frame, feed rollers mounted in the supplemental frame, 65 means for gearing said feed rollers in connection with said drive shaft, a conveyer mechanism mounted in the main frame, a sealing strip feeding and cutting mechanism mounted in the main frame and normally in an inoperative position, means operated by the article to be sealed as it is fed into the machine for putting said sealing strip feeding and cutting mechanism into operation to cut off a predetermined part of said strip, 70 means for feeding said strip into position to be engaged by the article fed into the machine and for moistening said part, means for compressing said part onto the edge portion of the article to be sealed, and means for 75 feeding the sealed article onto said conveyer. 80

15. In a machine of the class described, a main frame comprising a base member and inner and outer vertical frame members, a drive shaft mounted in the outer frame 90 members, a plurality of feed rollers mounted in the inner vertical frame members, a supplemental frame movably mounted on the drive shaft and capable of movement toward and from the main frame, feed rollers 95 mounted in the supplemental frame, means for gearing the feed rollers in the main frame in connection with the drive shaft, means for gearing the feed rollers of the supplemental frame in connection with the drive shaft, means for feeding a gummed sealing strip into the machine, means for cutting off a predetermined part of said strip, said sealing strip, feeding and cutting means being normally in an inoperative position, and devices operated by the articles to be sealed as they are fed into the machine for putting said sealing strip feeding and cutting mechanism into operation. 100

16. In a machine of the class described, a main frame comprising a base member and inner and outer vertical frame members, a drive shaft mounted in the outer frame, members, a plurality of feed rollers mounted in the inner vertical frame members, a supplemental frame rotatably mounted on the drive shaft and movable toward and from the main frame, feed rollers mounted in the supplemental frame, means for gearing the feed rollers in the main frame in connection with the drive shaft, means for gearing the feed rollers of the supplemental frame in connection with the drive shaft, means for feeding a gummed sealing strip into the machine, means for cutting off a predetermined part of said strip, said sealing strip feeding and cutting means being normally in an inoperative position, devices operated by the articles to be sealed as they are fed into the machine for putting said 110

sealing strip, feeding and cutting mechanism into operation to cut off a predetermined part of said strip, means for feeding said part into position to be engaged by the article to be sealed as it is fed into the machine and for moistening said part, and means for compressing said part onto the edge portion of the article to be sealed.

17. In a machine of the class described, a main frame comprising a base member and inner and outer vertical frame members, a drive shaft mounted in the outer frame member, a plurality of feed rollers mounted in the inner vertical frame members, a supplemental frame pivotally mounted on the drive shaft and movable toward and from the main frame, feed rollers mounted in the supplemental frame, means for gearing said feed rollers in connection with the drive shaft, means for giving one of said feed rollers an intermittent movement toward and from the corresponding roller in the main frame, a stop device mounted in the supplemental frame and movable toward and from the main frame, means mounted in the inner frame members for feeding a gummed sealing strip into the machine, means for cutting off a predetermined part of said strip, a geneva and geneva crank mounted in the inner frame members, means for gearing the geneva in connection with said sealing strip feeding and cutting means, means in operative connection with the geneva for moving it transversely of the machine and out of engagement with the geneva crank, devices operated by the article to be sealed as it is fed into the machine and in operative connection with said geneva to hold the same in position to be engaged by the geneva crank and operate the sealing strip feeding and cutting means to cut off a predetermined part of said strip, and means for feeding said part into position to be engaged by the article to be sealed as it is fed into the machine and for moistening said part.

18. In a machine of the class described, a main frame, a drive shaft mounted therein, feed rollers mounted in the main frame, means for gearing said feed rollers in connection with said drive shaft, a supplemental frame pivotally mounted on said shaft and movable toward and from the main frame, feed rollers mounted in the supplemental frame and adapted to coöperate with the feed rollers in the main frame, means for gearing said feed rollers in connection with the drive shaft, a sealing strip feeding and cutting mechanism mounted in the main frame, a geneva and geneva crank mechanism mounted in the main frame and in operative connection with the sealing strip feeding and cutting means, and devices operated by the article to be sealed as it is fed into the machine for holding said geneva in position to be engaged by the crank to operate the sealing strip feeding and cutting means, and devices operated by the article to be sealed as it is fed into the machine for holding said geneva in position to be engaged by the crank to op-

erate said sealing strip feeding and cutting means to cut off a predetermined part of said strip.

19. In a machine of the class described, a main frame, a drive shaft mounted therein, feed rollers mounted in the main frame, means for gearing said feed rollers in connection with said drive shaft, a supplemental frame pivotally mounted on said shaft and movable toward and from the main frame, feed rollers mounted in the supplemental frame and adapted to coöperate with the feed rollers in the main frame, means for gearing said feed rollers in connection with the drive shaft, a sealing strip feeding and cutting mechanism mounted in the main frame, a geneva and geneva crank mechanism mounted in the main frame and in operative connection with the sealing strip feeding and cutting means, devices operated by the article to be sealed as it is fed into the machine for holding said geneva in position to be engaged by the crank to operate said sealing strip feeding and cutting means to cut off a predetermined part of said strip, and means for feeding said part into position to be engaged by the article to be sealed and for moistening said part.

20. In a machine of the class described, a main frame, a drive shaft mounted therein, feed rollers mounted in the main frame, means for gearing said feed rollers in connection with said drive shaft, a supplemental frame pivotally mounted on said shaft and movable toward and from the main frame, feed rollers mounted in the supplemental frame and adapted to coöperate with the feed rollers in the main frame, means for gearing said feed rollers in connection with the drive shaft, a sealing strip feeding and cutting mechanism mounted in the main frame, a geneva and geneva crank mechanism mounted in the main frame and in operative connection with the sealing strip feeding and cutting means, devices operated by the article to be sealed as it is fed into the machine for holding said geneva in position to be engaged by the crank to operate said sealing strip feeding and cutting means to cut off a predetermined part of said strip, and means for feeding said part into position to be engaged by the article to be sealed and for moistening said part.

21. In a machine of the class described, a main frame, a drive shaft mounted therein, feed rollers mounted in the main frame, means for gearing said feed rollers in connection with said drive shaft, a supplemental frame pivotally mounted on said shaft and movable toward and from the main frame, feed rollers mounted in the supplemental frame and adapted to coöperate with the feed rollers in the main frame, means for

- gearing said feed rollers in connection with the drive shaft, a sealing strip feeding and cutting mechanism mounted in the main frame, a geneva and geneva crank mechanism mounted in the main frame and in operative connection with the sealing strip feeding and cutting means, devices operated by the article to be sealed as it is fed into the machine for holding said geneva in position to be engaged by the crank to operate said sealing strip feeding and cutting means to cut off a predetermined part of said strip, means for feeding said part into position to be engaged by the article to be sealed and for moistening said part, means for compressing said part onto the edge portion of the article to be sealed the rear end portion of the machine being provided with a conveyor mechanism, and means for feeding the sealed article onto said mechanism.
22. In a machine for sealing folders, circulars and the like, means for intermittently feeding articles to be sealed into the machine, means for feeding a gummed sealing
- strip into the machine, means for cutting off a predetermined part of said sealing strip, said feeding and cutting means of said strip being normally in an inoperative position, and means operated by the article to be sealed as it is fed into the machine for putting said gummed sealing strip feeding and cutting means into operation to cut-off a predetermined part of said strip, means for moistening said cut-off portion of the strip and feeding it into position to be engaged by an article to be sealed as it is fed into the machine, and means for folding and compressing said portion of the sealing strip onto the edge portion of said article and for feeding the same through the machine.
- In testimony that I claim the foregoing as my invention I have signed my name in presence of the subscribing witnesses this 16th day of April, 1918.
- DAVIS MARINSKY.
